Patented Jan. 23, 1917.

UNITED STATES PATENT OFFICE.

MAXWELL M. UPSON, OF ENGLEWOOD, NEW JERSEY, ASSIGNOR TO RAYMOND CONCRETE
PILE COMPANY, OF NEW YORK, N. Y., A CORPORATION OF NEW JERSEY.

CONCRETE PILING AND PILING ELEMENT.

1,213,437.

Specification of Letters Patent. Patented Jan. 23, 1917.

Application filed July 23, 1909. Serial No. 509,111.

To all whom it may concern:

Be it known that I, MAXWELL M. UPSON, a citizen of the United States of America, and a resident of Englewood, New Jersey, have invented certain new and useful Improvements in Concrete Piling and Piling Elements, the principles of which are set forth in the following specification and accompanying drawing, which discloses the form of the invention which I now consider to be the best of the various forms in which the principles of the invention may be embodied.

This invention relates to concrete piling and piling elements for foundations, walls, cribs, coffer-dams, piers, wharves, bridges, bulkheads, buildings and the like.

The object of the invention is a practical construction, physically and economically, of said nature for such purposes, and the invention consists of the structures herein-after disclosed and claimed.

Of the drawings, Figure 1 is a horizontal section (at 1-1, Fig. 2) of a plurality of concrete piles or piling elements constructed in accordance with the invention and combined to form piling; Fig. 2 is a partial elevation of the same, and Figs. 3 and 4 are horizontal sections along the line B—B of Fig. 2.

The following prior art has the stated disadvantages. Concrete piles with simple integral concrete tongue-and-groove interlock are manifestly weak at the joint, and therefore are not well adapted to resist strains at right angles to their length. Combination steel and concrete piles wherein the steel comprises a structure forming a connecting bare steel web and a container for the concrete, either both, or one or the other, and wherein there is a metal interlock, are excessively expensive and lack the mechanical advantage of a uniform, thick and stable concrete structure. So also with sheet piling entirely composed of steel, which is not sufficiently rigid unless the mass of the material is increased to an economically prohibitive degree, as by increasing the thickness of the sheets or by providing extra angles to withstand the greatest strains. In any case, steel piling is most expensive, and has a short life resulting from rust and salt-water erosion; and protection of the steel by

coatings of concrete simply increases its said excessive cost.

This invention involves a concrete pile, as a piling element, which needs no metal parts extending through it in the line of piling, or from top to bottom, and which is in and of itself essentially a concrete pile, preferably steel-reinforced vertically, and having a metallic lock or interlock to withstand right angle strains, but practically and substantially lacking a continuous steel structure, as distinguished from steel piling. The economies and mechanical advantages and the modes of making and use of this novel combination concrete-steel pile will be apparent from a study of the following description.

The concrete piles shown may consist of the material commonly used, *i. e.*, comprising cement, sand, and broken stone or gravel, the last being preferably used for economy. The piles may be molded in any known way, and may, and preferably do, contain the usual vertical steel reinforcing rods or equivalents shown at Y as mutually supported by wires or stirrups X, in the usual way. The concrete of the pile is indicated in Fig. 1 in section by the cross-hatching. Contribution to the steel reinforcement of the piling elements is made by the steel interlocks herein-after described, which may be molded in the concrete at the same time as the ordinary reinforcing rods above mentioned, the interlocks being preferably engaged with the supporting stirrups of the vertical reinforcing rods as shown.

The chief characteristic of my combination of metal interlock with a concrete pile is that the interlocks need be placed only where it is desired that they perform their locking function, thus saving cost; the piling essentially consisting chiefly of the concrete piles; and also that the interlock is so combined with the concrete of the pile itself as to permit the same to be so made of concrete in the ordinary way except in so far as concerns the embedding or reception of the metal interlock itself and also such modifications of the interlocking face of the pile as may result from such embedding or adaptation for reception, or as may be necessary to permit the interlock to discharge its function. This invention makes it possible

to use as a piling element the ordinary concrete pile, without any external covering or container and capable of being grounded in the manner usual in the case of concrete piles.

I have found that a concrete wall or piling made up of the piles of this invention, is substantially even stronger and more rigid than a continuously molded wall of concrete would be. The advantage in installation of this substitute for a continuously molded wall, will be clear from a consideration of the fact that piles of this invention are manufactured as separate individual units either in or out of their grounded positions, but preferably out, and before grounding; and when so pre-molded they can be readily handled, and grounded in the ordinary way in which concrete piles are sunk, as by water-jetting or driving, or both, and without the necessity of the preliminary trench-excavation required for a continuously-molded concrete wall.

The construction and molded location of the metallic interlocks, which may be, and in many cases preferably are, of rolled steel of any shape suitable for interlocking, will be understood from a consideration of such members as A, B, and B¹, for example, at the left of Fig. 1. These members do not extend continuously in the horizontal line of piling through the molded concrete pile, (see Fig. 2 also) but have only sufficient shanks S, S, to cause sufficiently strong embedding in the mass of concrete of the pile and to provide lateral bearing surfaces against the concrete to resist strains tending to displace them laterally,—such strains, for example as would shear off the simple integral concrete tongue C, or the walls D, D, of the groove for said tongue, if the metal interlocks were not molded in as stated. The concrete tongue C, and groove M, (walls D, D,) are used, if desired, (in addition to the principal features of the invention) for the purpose of assisting in closing the joint between the piling elements while permitting the presence of the vertically-short interlocks A, B, to be described. Other means for closing the joint to be described, may be used if desired, with or without the simple integrally cast concrete tongue and groove. The metal interlocks are suspended in the mold in any way customary with ordinary reinforcements. In the lack of a steel web integrally connecting A and B in a single pile or piling element, this lack being one feature of substantial economy, other and cheaper means may be employed as herein-after described, if desired, to increase resistance to strains tending to pull the interlocks out of the concrete; an important object of the interlocks being to cause the pile to resist strains at right angles to its vertical length, including those in line with the

piling as well as those transverse to it, when desired, or either, if desired. Thus A and B may have one or more lateral projections on their inner ends as indicated at E, E; or tie-rods F (Figs. 1 and 2) may connect A and B. Other such means are also disclosed and will be described. In cases, however, where it is necessary only to provide against transverse strains, the metallic interlock need not be double in the sense that it also resists longitudinal strains in the line of the piling. The metal interlocks may be used as guides for successively grounding adjacent piles, (the vertically disposed sections to be described being in vertical alignment for this purpose), so that when one piling element is in place in the ground, the next is lifted in place so that the interlock registers, the second pile being then sunk alongside the first. After the grounding of the two adjacent piles, the free space at the joint in the vicinity of the interlock may be filled with hydraulic cement termed grout, (indicated by dots in Fig. 1), and consisting of cement, sand and water in customary proportions, lacking the broken stone forming a constituent of the concrete of the piles themselves. This grout sets with the two adjoining concrete piles, closing the joint water-proof to make a substantially continuous wall of molded concrete, and also surrounds the metal interlock with the result of protecting it from rust or erosion by the action of salt water. By forcing the grout down into the bottom of said space, if desired, the pile-footing can be improved so as to increase the carrying capacity of the grounded structure. The grouting of the joint, or of the concrete tongue-and-groove construction C, M or both, permits one of the preferred constructions as shown in Figs. 1, 2, 3, and 4. The section B—B of Fig. 2 (Figs. 3 and 4) shows a case where hook-interlock A, does not extend beyond the face of the molded concrete pile.

In Fig. 3 is shown a permanent thin sheet-steel hollow member G, which serves not only as the mold-core for a passage H, extending from end to end of the concrete pile and opening through the hollow of hook-interlocks A, but serves also as a wearing-guide for the coöperating member B¹ or B to reinforce the wall of the passage in the concrete pile. This hollow steel core G may be bent as a core for the mold to form a hole in the concrete between the relatively vertically-disposed metallic interlocking members as shown in Fig. 3, said hole having the same diameter as that of the inside of the hook-portion of member A. Or as shown in Fig. 4 the hollow core G¹ may be larger than the inside of the hook portion, so that the wall of the hole H¹, between A, A, sets back of the inside of the hook

portion of A. In the latter case the hook-
portions of A will take all the wear, and core
G¹ may be removed after the molding of the
pile, if not desired as a permanent reinforce-
5 for the passage-wall. Before removal how-
ever, it has served the purposes of producing
a passage H, in perfect alinement with the
hooked portions of A, and of supporting
said hook members during the process of
10 casting the concrete pile. The vertical
spaces, passages, or grooves between the ver-
tically disposed hook members A, may be
cored to any other desired shape, if desired.

The number of vertical interlocks A, one
15 or more, and the vertical length of each,
the longitudinal width of the shank S, if
used; and the dimensions of shank-end in-
terlock F, if used, are matters of practice
determined in each case by calculations as
20 to the pull and strains to which any partic-
ular installation of piling will be subjected
during and after installation. The same is
true as to the other interlocks B¹, corre-
sponding with members A, because verti-
25 cally successive members B¹ will be guided
into their appropriate coöperating members
A, on account of the alinement established
by the substantially extended vertical en-
gagement of the first vertical pair. It is
30 clear that after the grouting described
above, in the space around the interlock, the
joint is as watertight as if the metal inter-
lock were vertically continuous from top to
bottom, and it is clear also that substantial
35 economy of steel results from the molding
of the concrete of the pile into the vertical
and horizontal spaces between the interlocks.
(In Fig. 2 such concrete is shown above and
below, and between the metallic interlocks).
40 The steel members A, B, B¹ (molded in the
piling elements), on the other hand, pro-
vide interlocking means capable of with-
standing strains not possible to be borne by
interlocks consisting of simple integral con-
45 crete portions of the piles. Finally, the pil-
ing itself is not only substantially as strong
as sheet-steel piling, but provides that in-
creased stability and carrying capacity
50 which could be furnished otherwise only
by a continuously molded concrete wall or by
sheet steel piling plastered thickly on both
sides with concrete. The vertical or hori-
zontal separation of the interlocking mem-
55 bers, or both, permits the casting of a homo-
geneous reinforced concrete pile which is
much stronger than a pile in which the in-
terlocking members extend throughout the
whole length or width and sever it into two
60 parts. In other words, it permits the pile
to be made integrally of concrete as distin-
guished from a mere plastering of concrete
over an ordinary sheet steel pile.

Many modifications may be employed. A
65 and B are shown as molded in concrete
tongue C, and groove M¹ respectively; but

they might be reversed. They are shown
as extending only to the face of the pile, but
they might extend beyond it, as at J, K,
and L. Each pile may have two grooves,
70 N, O, instead of one groove M and a tongue C;
and the larger space afforded by result-
ing adjoining grooves M¹, N, is useful in
most readily permitting a thorough grout-
ing or even concrete filling in of the joint
75 and metal interlocks. Or the pile may have
flat joint-faces, a hook interlock J¹ being
entirely embedded in the concrete of the
pile, and an interlock K having only its
shank S embedded, its bill projecting be-
80 yond the flat face. Or ordinary steel chan-
nels P, Q, R may be embedded (as partial
equivalents of hooks A), one, as P or R,
extending only to a joint face of a grooved
pile, and the other, as Q, extending beyond
85 the opposite grooved face, and both Q and R
coöperating together in a large grouting
space T formed by grooves in adjacent pile-
faces. The grooves in the piles, which
grooves contain the interlocks, such as the
90 space V, are cored in practice by means of
their sheet steel forms bent to shape, such as
U, in order to avoid the expense of first
shaping solid cores. These hollow or thin
sheet metal cores, as U, may be left in place
95 to serve as wearing guides for the interlocks,
particularly such as K or L which engage
with only one edge of their respective co-
operating members P or R.

In some cases a pile can be molded with
only one metal interlocking member, as for
example the I beam shown at W, so that
this single member, molded in one of the
piling elements, can be engaged in a groove
in the joint face of another piling element.
The I beam is lodged in a cavity formed
100 by the thin metal core or reinforcer U¹.

Such cases are where the thicknesses of
the concrete pile and of the groove-walls
D¹, D¹ are sufficient, and the interlocking
groove and member W are sufficiently nar-
row, so that the walls or projections D¹, D¹
will not be sheared off by transverse strains.
In such cases the effect is as if each of
both adjoining joint-faces of adjacent piles
had its own separate metallic interlock
110 molded in it, and as if the two interlocks
engaged each other. But in this disclosure,
the single interlocking member requires
115 much less of the expensive material (as
rolled steel) than when each pile has two
interlocking members, one for each joint-
face, as A, B. This construction at W, is
practicable as compared with an all-con-
crete interlock, on account of the great
120 strength of the small mass of steel, which
small mass also permits a large and strong
mass of concrete at D¹, D¹. Whenever nec-
essary or desirable the concrete portions D¹,
D¹ may be strengthened by molded-in-steel
125 reinforcing members such as Z, Z¹. In this
130

particular embodiment of the invention, very great economy of steel can be had even if the steel member W extends uninterruptedly from top to bottom of the pile. 5 If the reinforces Z, Z¹ be used, they may be simply the ordinary wires or stirrups.

In order to save the cost of grout for filling the interlocking spaces and protecting the metallic interlocks, the stirrups or 10 other metallic interlocks may be extended, in molding, as at X¹, beyond the flat face of the pile, and the mold be constructed so that the broken-stone mixture will entirely surround the interlocking members to 15 form the strong and rigid interlocking projection K¹ engaging in the groove T¹ in the adjacent pile. The walls of the groove T¹ are in this case preferably reinforced by molded-in metallic members, as Z². Another 20 way of avoiding expensive grouting, and at the same time to obtain metallic interlocking of grooved concrete piles, is to prepare an independent locking member consisting of a concrete column having the sheet metal 25 envelop A¹ of double-wedge form to cooperate in the correspondingly formed pile groove A². If desired, this member A¹ may be cast integrally with a piling element, as the one shown at its right, and in such case 30 the groove-reinforce Z² may be omitted from that pile, as shown. When not cast with a piling element, member A¹ may be driven into the ground in one pile to serve as a guide for the grounding of the adjacent pile.

In case a grounding guide is not necessary, an interlock such as the hollow metal form C¹, of the double-wedge form shown, may be placed in the edge of the pile 40 grooves, and then grout may be applied both inside and outside of the hollow form, the reinforcements Z³, Z³ being employed to strengthen the pile grooves.

Except for convenience in locating the 45 vertically-disposed interlock sections in their proper vertical positions, it is not absolutely necessary that the lefthand side of sections W be pre-molded in the pile, and they might be lowered, after the 50 grounding of the pile, into a groove molded therein; although in such case W may be subsequently grouted in the groove, either before or after the succeeding grooved pile has been grounded along W as a guide.

Except for the economy of steel, it is not necessary for the respective interlocks to be vertically disposed in sections, provided that the pile retains its integrity as a concrete pile, as by having sufficient extent of 60 concrete interposed between the horizontal series of interlocks of a given pile, and substantially from top to bottom between said series. In no case may the concrete structure of the pile be substantially weakened as by in effect splitting it in two in

a vertical plane. The portions of the interlocks which cross the pile-joints form locks against water or soft material.

In any case within the invention, the interior of the pile must at least contain a 70 mass of concrete essentially interlocking the respective parts of the concrete pile. It is generally advisable, in any case, to have the horizontal concrete space as wide as possible, consistent with the proper embedding of the interlocks in the joint-faces 75 to resist pulls at right angles to the vertical length of the pile.

The ultimate product of the invention is a piling which is all-concrete, as concerns all 80 but the desirable ordinary reinforcement, and the metallic interlocks and the latter are preferably completely protected with cement, such that the effect, as to waterproofing and perpetual life, is that of a solid 85 concrete wall. This piling furthermore resembles a continuous concrete wall in being of uniform thickness, not increased at the joints, lacking any outer covering or container, and having full strength both in the 90 plane of the piling and at angles therewith. This piling may be adapted to any desired angle, by merely changing the shape of the molds for the individual piles. In short, it may be used under any conditions 95 where steel piling is now used, but with not only high comparative economy, but with greatly increased stability and carrying capacity. Not only is it much more economical for a given height of pile, but the economy is multiplied as a result of the fact that 100 a given height of pile has a greater carrying capacity, owing to the massive character of the concrete pile element and its substantial thickness.

The expression "concrete pile" is used herein in its ordinary sense as meaning a pile of molded concrete, preferably with integral metallic reinforcing means, but which is complete in and of itself, in that no casting, covering or any exterior protection means is desirable or necessary. The expression "interlock" is used herein to mean a lock which resists pulls at right angles to the height of a piling element, either longitudinally or transversely of the line of piling, or both.

I claim:

1. A piling element consisting of a pile composed of concrete and having embedded 120 in it metallic interlocks for the respective joint faces, said interlocks being separated by a concrete filled pile space in the direction of the piling, and such interlocks consisting of a vertically disposed series of sections separated from each other by the pile concrete, and co-operative with adjacent piling elements.

2. A piling element comprising a pile composed of concrete and having embedded 130

- in it at each of two of its respective sides, separate metallic members, each constructed to interlock with adjacent piling elements.
3. A piling element comprising a pile composed of concrete and having a vertical metallic interlock embedded in it in the plane of the piling but extending only partially through the pile in the direction of the piling.
4. A piling element consisting of a pre-molded pile composed essentially of concrete and having embedded in it a rolled steel member not affecting the integrity of the concrete structure, but extending outside the concrete and adapted to coöperate with a 15 succeeding piling element to resist strains at right angles to the vertical length of the pile.
5. A piling element comprising a pile composed of concrete and having embedded in its side a separate metallic member in vertically disposed sections each constructed to interlock into an adjacent piling element.
